CYLINDER LOCK

Original Filed March 31, 1933

UNITED STATES PATENT OFFICE

2,070,233

CYLINDER LOCK

Samuel A. Liss, Philadelphia, Pa., assignor to
Briggs & Stratton Corporation, Milwaukee,
Wis., a corporation of Delaware

Original application March 31, 1933, Serial No.
663,805, now Patent No. 2,003,086, issued May
28, 1935. Divided and this application June
29, 1934, Serial No. 733,050

2 Claims. (Cl. 70—46)

This invention relates to improvements in locks and refers more particularly to cylinder locks of the type forming the subject matter of Patent No. 2,003,086, issued May 28, 1935, of 5 which this application is a division.

As in the aforesaid application, it is a general object of this invention to provide a lock having exceptional security against picking and decoding.

10 More specifically, it is an object of this invention to provide a lock in which the cylinder is secured against movement by an auxiliary locking member or tumbler, or a plurality of such locking members or tumblers, biased to an operative position effecting interengagement between the cylinder and its casing and positively held in such position by any one of the regular key operable tumblers in any but fully retracted position.

20 With the above and other objects in view which will appear as the description proceeds, this invention resides in the novel construction, combination and arrangement of parts substantially as hereinafter described and more 25 particularly defined by the appended claims, it being understood that such changes in the precise embodiment of the hereindisclosed invention may be made as come within the scope of the claims.

30 The accompanying drawing illustrates two complete examples of the physical embodiment of the invention, constructed according to the best modes so far devised for the practical application of the principles thereof, and in which:

35 Figure 1 is a longitudinal section view through a lock embodying this invention;

Figure 2 is a cross section view taken through Figure 1 on the plane of the line 2—2;

Figure 3 is a longitudinal section view taken 40 through Figure 1 on the plane of the line 3—3;

Figure 4 is a perspective detail view showing the lock in cross section with the cylinder partially turned from its locked position to more clearly illustrate the relative position of the various parts;

45 Figure 5 is a perspective view showing the releasable holding means at the inner end of the lock for removably securing the cylinder in position;

50 Figure 6 is an enlarged side view of one of the tumblers employed in the lock, shown in Figures 1 to 4 inclusive;

Figure 7 is a perspective view of one of the auxiliary locking tumblers or locking members;

55 Figure 8 is a longitudinal section view similar

to Figure 1, but having a master key inserted therein which is equipped to release the cylinder holding means;

Figure 9 is a longitudinal section view similar to Figure 1, showing a modified embodiment 5 of this invention;

Figure 10 is a view partly in longitudinal section and partly in elevation, taken on the plane of the line 10—10 of Figure 9;

Figure 11 is a cross section view through Figure 10 9 on the plane of the line 11—11; and

Figure 12 is an enlarged perspective view of one of the tumblers used in the modified form of lock shown in Figures 9, 10 and 11.

Referring now more particularly to the accompanying drawing, in which like numerals indicate like parts throughout the several views, the numeral 5 designates the mounting member or casing of the lock, bored as at 6 to receive a lock cylinder 7. The cylinder is removably secured in the mounting member or casing by a 20 flange 8 at the front of the cylinder engaging in a counterbore 9, and a releasable retaining member 10 mounted on the inner end of the cylinder and engageable with the adjacent end 25 of the mounting member or casing.

An angle plate 11 fixed to the inner end of the cylinder to provide means for transmitting rotation to mechanism controlled (not shown), 30 slidably mounts the retaining member, and a spring 12 yieldably urges the same to a position projecting its outer end over the inner edge of the bore 6. This releasable cylinder securing means forms the subject matter of a copending application.

To enable withdrawal and insertion of the cylinder, the retaining member 10 may be moved inwardly against the action of its spring 12 by the extended end of a special or master key 13, shown in Figure 8. As shown, the extreme 40 end of the key 13 engages the retaining member and moves the same inwardly against the action of its spring.

The regular key 14, shown in Figures 1 and 9, is of insufficient length to engage the retaining member, so that during normal operation of the lock, the cylinder does not become 45 detached.

To receive the key, the cylinder is equipped with a keyway 15, which extends inwardly from 50 the front of the cylinder with its bottom opening to the cylindrical surface of the cylinder, although it is to be understood that for the purposes of the invention, the keyway need not break through the cylinder wall. The keyway 55

communicates with a plurality of transverse tumbler receiving recesses or pockets 16 in which individual key operable tumblers 17 are slidably mounted for actuation by either the 5 special or master key 13, or the regular key 14.

In the embodiment illustrated in Figures 1 to 4 inclusive, the key operable tumblers are of the pin type, circular in cross section, as specifically shown in Figure 6, whereas in the 10 embodiment illustrated in Figures 9 to 11 inclusive, the tumblers 17 are of the flat plate type, specifically shown in Figure 12. This is the only difference between the two modifications illustrated.

15 Individual springs 18, confined between the outer ends of the tumblers and a plate 19 embedded in the body of the cylinder across the open tumbler recesses and flush with the cylindrical surface of the cylinder, yieldably project 20 the tumblers inwardly toward the keyway 15. In the absence of a key, the inner ends of the tumblers rest on the substantially closed bottom of the tumbler recesses or pockets.

The circular pin type tumblers have their 25 inner ends pointed or of conical shape to afford proper engagement of the bittings on the key.

It is observed that no portion of the key operable tumblers projects beyond the periphery of the cylinder, the locking engagement between 30 the cylinder and its casing being afforded by auxiliary tumblers or locking members 20, which are slidable radially in slots 21 formed in the cylinder at right angles to the tumbler recesses or pockets 16 and communicating therewith at 35 their inner edges.

As best shown in Figure 7, these auxiliary tumblers or locking members are substantially in the form of plates with their outer edges reinforced and increased in thickness by reinforcing 40 binders 22, the outer portions of which provide rounded edges engageable in longitudinal grooves 23 formed in the casing or mounting member and opening to its bore 6.

Projecting from each end of the auxiliary 45 tumblers or locking members are lugs 24, with which springs 25 engage to yieldably urge the auxiliary tumblers or locking members outwardly and into their respective grooves 23. The springs 25 are mounted in pockets 26 in the 50 cylinder near the ends of the slots 21 and have their inner ends seated on the bottoms of said pockets and their outer ends bearing against the lugs 24.

When the cylinder is in its normal locked position, which is conveniently indicated by a spring 55 detent 27 carried at the front end portion of the cylinder and engageable in a depression 27' in the casing, the outer edges of the auxiliary tumblers or locking members are projected by 60 the springs 25 into the grooves 23. The distance between the inner edges of the auxiliary tumblers or locking members in this position is just slightly greater than the diameter of the pin tumblers or the width of the plate tumblers 65 to permit the key operable tumblers to be raised and lowered as required by the insertion and withdrawal of the key.

When the key is removed, the key operable tumblers block inward movement of the auxiliary tumblers and thus positively hold the same in their operative positions, effecting interengagement between the cylinder and casing.

To free the auxiliary locking tumblers or locking members for inward movement and 75 thereby free the cylinder for rotation in its

casing, the key operable tumblers are retractable by a proper key to unlocked positions at which annular grooves 28 in the pin type tumblers and notches 29 in the plate type tumblers are aligned with the inner edges of the auxiliary tumblers or locking members. 5

When all of the tumblers are so moved to their inoperative positions by a proper key and all of their grooves or notches 28 and 29 respectively, align with the auxiliary tumblers or locking members, it is possible to turn the cylinder as the rounded outer edges of the auxiliary tumblers or locking members cam themselves out of their respective grooves 23 in the casing, the inner edge portions of the locking members entering the grooves or notches in the tumblers. 10 15

The annular grooves or notches in the tumblers are of sufficient depth to allow the full inward projection of the auxiliary tumblers or locking members necessary to release the cylinder for rotation, but have their sides sharply defined so that if an improper key is used, and any one tumbler is not moved to its proper inoperative position, such tumbler will hold the auxiliary tumblers or locking members in their 20 operative positions. It is thus extremely difficult, if not utterly impossible, to pick the lock of this invention.

To further guard against the possibility of 30 picking, the tumblers are equipped with false grooves and notches 28' and 29'. These false notches and grooves are of insufficient depth to allow the complete retraction of the auxiliary tumblers or locking members. 35

If desired, certain of the tumblers may be equipped with two proper or sufficiently deep grooves or notches, as shown in Figures 6 and 12, for the purpose of master keying a series of locks, and in Figure 8, the master or special key 40 13 is shown holding two of the tumblers at different heights, but in proper unlocking positions.

From the foregoing description taken in connection with the accompanying drawing, it will 45 be readily apparent to those skilled in the art to which this invention appertains, that the lock here disclosed, affords a very secure manner of locking the cylinder against rotation in its casing, and that picking or decoding of the lock by 50 any known method is precluded.

What I claim as my invention is:

1. In a lock, a bored mounting member, a lock cylinder movable therein and having transversely extending tumbler guideways, a plurality of key 55 operable tumblers guided at their sides in said guideways for linear movement transversely of the cylinder, and an auxiliary tumbler movable in a plane angular to the plane of movement of said plurality of key operable tumblers biased to 60 an operative position interlocking the cylinder and its mounting member and positively held in its operative position by the unimpaired thickness of any one of said plurality of key operable tumblers in any but properly retracted 65 position irrespective of whether such position is one way or the other from the properly retracted position, the thrust of said auxiliary tumbler being transmitted through the solid unimpaired thickness of said key operable tumbler directly to 70 said guideway.

2. In a lock, a bored mounting member, a lock cylinder rotatable in the mounting member bore and having a longitudinally extending keyway and a plurality of transversely disposed 75

tumbler guideways, a plurality of key operable tumblers guided and supported in the guideways for movement transversely of the cylinder in substantially a common plane longitudinal to the cylinder and with one end of the tumblers accessible from the keyway to be engageable by a key inserted into the keyway, spring means acting on the other ends of the tumblers to press the same toward the keyway, a pair of diagonally opposed locking members movable radially in recesses in the cylinder at opposite sides of the plurality of key operable tumblers and engageable by the key operable tumblers at their inner edges, spring means to project the locking members outwardly from the cylinder into engage-

ment with longitudinal grooves in the mounting member to secure the cylinder against rotation, the outer edges of the locking members and the grooves receiving the same being so shaped as to cam the locking members inwardly upon rotation of the cylinder when said key operable tumblers are not blocking inward movement of the locking members, and the key operable tumblers being formed with narrow portions adapted to be aligned with the locking members to receive their inner edge portions and allow inward movement thereof upon movement of the tumblers to unlocked positions by a proper key inserted into the keyway.

5

SAMUEL A. LISS.
